UNITED STATES PATENT OFFICE.

FREDERICK W. CONSTANTINE, OF ST. ANNES-ON-SEA, AND THOMAS GEORGE KAY, OF BOLTON, ENGLAND.

DRAG DEVICE FOR SPINNING, DOUBLING, TWISTING, AND LIKE MACHINES.

Application filed September 25, 1923, Serial No. 664,717.

To all whom it may concern:

Be it known that we, FREDERICK WILLIAM CONSTANTINE and THOMAS GEORGE KAY, subjects of the King of Great Britain, and 5 residents, respectively, of 5 Kensington Road, St. Annes-on-Sea, in the county of Lancaster, and 54 Back Cheapside, Bolton, in the county of Lancaster, England, have invented a certain new and useful Improvement 10 in Drag Devices for Spinning, Doubling, Twisting, and like Machines, of which the following description, having reference to the accompanying sheets of drawings, is a specification.

15 It relates to drag devices for the spindles of spinning, doubling, twisting and like machines in which the rotary motion of the spindle and the bobbin, tube or cop mounted upon same for the winding of the yarns or 20 threads thereon is effected by the pull of said yarns or threads when the same are being twisted and wound in manner well known, and our present invention consists in so forming the bearings for each of said 25 spindles that same may be automatically adjusted to regulate the pull upon said yarns or threads and the drag on the spindle parts carried by same, by the employment of a liquid within which said spindle rotates and 30 which liquid may be varied in depth so that it will cover more or less of the lower end of the spindle to exercise a greater retarding effect or less retarding effect thereon according to the depth of the liquid or 35 length of the spindle that is revolving in said liquid. The viscosity of this liquid is selected or arranged to be of such a character as to suit the particular class of yarn that is to be produced.

40 In order that our said invention may be readily understood we have hereunto appended sheets of drawings illustrative thereof, to which by figures and letters reference is made in the following description.

45 Fig. 1 is a front elevation showing only three spindles and their bearings, one bearing being in section the other two in elevation while all framework (except one rail C which supports the flyers) is omitted since 50 any appropriate form of framework may be made use of.

55 Fig. 2 is an end elevation (drawn to an enlarged scale) of the lower end of the spindle and the bearings for same, said bearings and parts being shown in section.

Fig. 3 is a sectional elevation showing the upper end of the bearings for the spindle such bearings being formed as is hereinafter explained.

Fig. 4 is a sectional end elevation showing 60 one spindle its bearings and parts in connection therewith in order to illustrate one method of adjusting the depth of liquid surrounding the lower end of the spindle according to what may be required to meet 65 the desired drag for the yarn.

Fig. 5 is a plan of the parts shown by Fig. 4.

Fig. 6 is an elevation of three spindles and 70 their bearings showing the modified form of device for adjusting or regulating the depth which the lower end of the spindle revolves. In this figure, A indicates the end frame, B the low longitudinal binding rail and C the 75 flyer rail.

In accordance with our invention we arrange the spindle 2 to revolve freely in bearings 3 which form a sleeve extending over the lower end of said spindle from the lowest extremity *a* to about its central part *b*. 80 Within this sleeve we place a viscous or other liquid to act as a retarding element upon the peripheral surface of the spindle during its rotary motions. We have found that the retarding actions of the viscous substances are greatest when the space *c* that exists between the peripheral surface of the spindle and the inner wall of the sleeve's cavity are smallest.

We have also found that good results are 90 attained for producing cotton yarns or threads of one hundreds count when the spindle is five sixteenths of an inch diameter mounted within a cylindrical tube with an opening of three eighths of an inch diameter and with oil of the nature of petroleum of .82 specific gravity.

The spindle 2 while resting upon the loose foot step 4 below the sleeve 3 will revolve 100 upon its pointed extremity thereon and at about its middle part it will take through the loose annular piece 5 which is supported by the shoulders of the enlarged openings at the upper end of the sleeve 3 by which arrangement not only is the spindle 2 allowed 105 more freedom but jerky vibrations are counteracted by this annular piece 5.

The sleeve 3 is fixed within a horizontal tube 6 (as by the two fixing nuts *w*, *w'*) 110 which extends lengthwise the spinning frame

to support the whole series of spindles and their sleeves, or to support numbers of same in sections throughout the whole length of said spinning machine. This longitudinal tube 6 acts as a lifter rail (and is hereinafter referred to as the lifter tube) so that by using guiding rods 7 to support said tube 6 the lifter motion at present in use may be employed for gradually lowering all the 10 spindles as the cop is being built or wound upon them from its heel *h* to its nose *f*.

The winding of the yarn, as is before stated is by the rotations of the flyer 8 through the leg 8^a of which the yarn or 15 thread *g* passes, and said flyer 8 is rotated by its driving band 9 in well known manner.

In an appropriate position upon the longitudinal tube 6 is mounted a vessel 10 within which the viscous liquid is placed and 20 which vessel 10 has its upper end level or approximately so with the highest point that the liquid within the sleeves 3 is desired to ascend, said vessel 10 being connected to the tube 6 by the duct or pipe 11.

25 In connection with the vessel 10 we employ the plunger or displacing member 12 which is suspended or mounted upon an arm 13^a extending horizontally from a sliding body part 13 in order that the stem 12^a of the member 12 may be secured thereon as shown by Figs. 1 and 4. This sliding part 13 has a bolt 14 taking through it and extending also through a slot 15^a in a vertical fixed bar 15 in order that upon the same bolt we may mount a plate 14^b as also a spring 14^c so that by the tightening of the nut 14^a upon said bolt 14 the spring will force the plate 14^b against one side of the bar while the head of the bolt 14 will pull 40 the sliding part 13 against the other side of the bar 15; thus said bar is gripped by these parts and therefore they are held against movement except as is hereinafter described.

45 When the spinning operations commence the spindles 2 will be in their highest positions as also will the lifter tube 6 so that as the winding operations proceed said tube 6 and its spindles will reciprocate a space 50 equal to the distance from the shoulder of the cop (at *h*) to its nose *f* while further gradually lowering until such reciprocations and continued lowering have progressed until the full length of the cop is wound in 55 manner well understood.

During the time that the winding of the thread to form the shoulder *h* of the cop is being carried out the lifter tube 6 will be in such position as to raise the vessel 10 so 60 that the displacing member 12 will cause the flow of the liquid therein to ascend to its highest position within the vessel 10 as well as within all the sleeves 3; thus at this time the greatest drag will be exercised over 65 or upon said spindles. As the lifter tube

6 descends to bring the spindles 2 so that the noses of the cops are being formed thereon then the vessel 10 will also descend and will leave the displacing member 12 suspended by its supports; thus the liquid will descend within said vessel 10 and will also descend within all the sleeves 3 hence the spindles will be relieved of such liquid and will run more freely during the winding of the noses of the cops thereon.

75 As the lifter tube is desired to descend gradually (in addition to its reciprocating movements) when each gradual stage of such descent is being carried out the base of the receptacle comes in contact with the projecting portion 13^b that extends from the sliding part 13 and will cause said part 13 (notwithstanding the gripping actions of the devices carried by the bolt 14) to slide or slip over the bar 15 from which it will be observed that the gripping actions of the parts described are only sufficient to secure the displacing member 12 in position against being floated and raised by the rising liquid within the receptacle 10 surrounding it.

80 Instead of making use of the receptacle 10 we may employ separate tubes 16 to take over the sleeves 3 within which the spindles are mounted as shown by Fig. 6, each sleeve 3 having its respective tube 6.

85 These sleeves 3 are then fixed upon the lifter rail 17 which is actuated in well known manner by means of the vertical lifter rod 17^a having its upper end fixed thereto being made to slide freely through the lower rail *b* of the machine, as actuated by the ordinary lifter lever 17^b, deriving its motion from the building mechanism well known. The tubes 16 are fixed upon an additional rail 18 and this rail 18 is supported by the vertical connecting rods 19 which are pivoted thereto at *x* and to the lever 20 at *x*¹. This lever 20 is pivoted at *x*² to a bracket 21 fixed to the end frame A and upon the central part of the bracket a projecting pin or stud 95 enters a slot 20^a formed in the lever 20.

100 The lever 17^b is caused to oscillate in known manner to form the building of the cop upon the spindles 2 and it also is caused to gradually lower the rail 17 so that the cops are built of the desired length also in manner well known. On account of the tubes 16 having to vary in accordance with the length of the nose of the cop from the point *h* to *f* of said cop during the movements of the spindles 2 while forming same we arrange the lever 20 to give double the motion (or such other proportion as may be thought advisable) to the rail 18 to what the lever 17^b gives to the rail 17; thus when the rail 17 is descending from the position shown by Fig. 6 so that the spindles are brought with the nose *f* of the cops opposite the guiding eyes in the arms 8^a the tubes 16 will have moved double the space; hence the 105 110 115 120 125 130 135 140 145 150 155 160 165 170 175 180

liquid within the sleeves 3 will also have lowered proportionately, by which arrangement we secure the variation in drag in the manner and for the purpose described in our 5 other arrangement.

When spinning comparatively heavy or strong threads or yarns it is obvious that the diameters of the lower ends of the spindles 2 will have to be increased as will also the 10 diameters in the openings of the sleeves 3 to receive same and such increase is carried out proportionate to the requirements of the threads that are to be produced, while variations in the actual drag upon the spindles 15 may be effected by increasing the space *c* that exists between the peripheries of the spindles 2 and the inner walls of the tubes 3 as above described.

The collars *t*, *t*¹ on the spindle 2 are to 20 prevent the displacement of said spindles when doffing.

The form of "flyer" which we preferably make use of in connection with our spindle revolving against the retarding actions of 25 a liquid, has its legs 8^a produced of resilient or springy wire which will yield when suddenly jerked by any irregularity in the pull of the thread thereon and thus avoid breakages of such thread.

30 Such being the nature and object of our invention what we claim is:—

1. In a spinning machine, a rotary flyer, means for rotating said flyer, a spindle arranged to be rotated by the pull of the 35 thread which is being wound upon it by the flyer, bearings for said spindle formed to receive a liquid which will surround a considerable portion of the lower part of the spindle, devices for regulating the extent 40 which said liquid is made to cover said lower end of the spindle, and means whereby said devices may be operated.

2. In a spinning machine, a rotary flyer, means for rotating said flyer, a spindle

mounted to rotate under or by the pull of 45 the thread which is being wound upon it by said flyer, a tube forming the bearings for said spindle, said tube being constructed to receive a liquid for surrounding the spindle, a cylinder connected to said tube by pipe 50 connections, a piston operating in said cylinder, a liquid within said cylinder and tube and means for operating said piston so that the liquid is thereby circulated within the cylinder, pipe connections and tube. 55

3. In a spinning machine, a flyer, means for rotating said flyer, a spindle upon which the thread carried by the flyer is wound, said spindle being rotated by the pull of 60 said thread, bearings for said spindle arranged to contain a liquid, said liquid, a cylinder with connections to the bearings for the spindle so that the liquid in said bearings may flow to said cylinder or vice versa, said bearings and said cylinder being 65 mounted upon a "lifter rail" said lifter rail, means for operating said lifter rail, a piston operating within the cylinder, and supports for said piston.

4. In a spinning machine, a flyer, means 70 for rotating said flyer, a spindle upon which the thread carried by the flyer is wound, said spindle being rotated by the pull of said thread, bearings for said spindle arranged 75 to contain a liquid, said liquid, a cylinder with connections to the bearings for the spindle so that the liquid in said bearings may flow to said cylinder or vice versa, said bearings and said cylinder being mounted upon a "lifter rail" said lifter rail, means for 80 operating said lifter rail, a piston operating within the cylinder, supports for said piston, bearings for said supports and means whereby said bearings may be operated by the lifter rail.

F. W. CONSTANTINE.
THOMAS GEORGE KAY.
